UNITED STATES PATENT OFFICE.

AUGUST W. PETERSON, OF HIGHWOOD, ILLINOIS.

STROPPING-MACHINE.

No. 869,981.

specification of Letters Patent.

Patented Nov. 5, 1907.

Application filed January 28, 1907. Serial No. 354,470.

To all whom it may concern:

Be it known that I, AUGUST W. PETERSON, a citizen of the United States, residing at Highwood, in the county of Lake and State of Illinois, have invented certain new and useful Improvements in a Stropping-Machine, of which the following is a specification.

This invention relates to improvements in a stropping machine or a device to be used for stropping blades of various kinds, such as razors, the blades of scissors and knives, and it consists in certain peculiarities of the construction, novel arrangement, and operation of the various parts thereof, as will be hereinafter more fully set forth and specifically claimed.

The principal object of the invention is to provide a stropping machine, which shall be simple and inexpensive in construction, strong, durable and efficient in operation.

Another object is to provide detachable means for holding and adjusting the blades of scissors so that they may be stropped by the device, and also for holding knives of various constructions for the operation of stropping the same.

Other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1 is a top plan view of a stropping machine embodying my invention, showing the attachment for holding the blade of a pair of scissors in position thereon. Fig. 2 is a plan view of the machine with the upper frame plate thereof removed, and showing the blade of a pair of scissors held by the attachment therefor and said attachment located in position on the rocking blade retainer. Fig. 3 is a horizontal sectional view taken about midway between the frame plates of the machine. Fig. 4 is a view in side elevation of the stropping machine, showing the attachment for the scissors in position in the retainer, and illustrating the opposite side of said attachment from that shown in Fig. 5. Fig. 5 is a detached view of the scissors holding attachment, showing one side thereof in elevation; and Figs. 6 and 7 are detail views of attachments for holding knife blades of different constructions.

Like numerals of reference, refer to corresponding parts throughout the different views of the drawing.

The reference numerals 10 and 11 designate the upper and lower plates, respectively, of the frame of the machine, and are preferably made alike and rectangular in shape and of skeleton form, as shown in Figs. 1 to 3, inclusive, of the drawing. Each of the frame plates 10 and 11 has at its rear end apertured lugs 12 through which screws may be passed for securing the frame to the wall of a room, or other suitable support.

The plates 10 and 11 are spaced apart, as shown in Fig.

4, and are secured together at their front ends by means of brace-bars 13 and near their rear ends by a brace-rod 14, and about midway between their ends by means of rods 15, on each of which rods, with the exception of the rod 14, is mounted an anti-friction roller or a sleeve 16, which are interposed between the plates 10 and 11. As shown, and as will be understood by reference to Figs. 1 to 3, inclusive of the drawing, each of the plates 10 and 11 is formed in its front portion 60 with an open space 17, and that the rear edge of said open spaces is provided with a rearwardly extending slot 18 enlarged at its front end for the operation of the blade retainer, and said slots are also for the reception and operation of projections on the upper and 70 lower ends of the blade retainer, as will be presently explained. Pivotaly mounted on the rod 14 near each of its ends, and near the inner surface of each of the frame plates 10 and 11, is a rocking member 19, each of which is substantially triangular in form and are 75 united together at or near their outer angles by means of rods 20, on each of which is mounted between the rocking members 19 an anti-friction roller or sleeve 21. The rocking members 19 are also connected together at or near their front angles by means of a rod 22, on 80 which is pivotally secured the blade retainer 23, which is preferably formed of a single sheet of metal bent or folded around the rod 22 and back upon itself, forming two plies 24 and 25 having at their front or free ends spaced apart jaws 26, which plies and jaws may be 85 suitably adjusted so as to hold the blade or blade carrying attachment between said jaws by means of a bolt 27 and a nut 28, which bolt passes through the said plies. The blade retainer 23 may have located between its plies 24 and 25 a vertically extending rod, 90 the ends or projections 29 of which will extend through the contracted or rear portions of the slots 18 in the frame plates.

By reference to Figs. 1 to 3, inclusive, it will be seen that a leather strop 30, which may be of a width about 95 equal to the space between the frame plates 10 and 11, is passed around the rollers or sleeves 21 on the rods 20 which the rocking members 19 carry, and is then extended between the sleeves 16 on the rods 15, which are spaced apart at a sufficient distance, so that the 100 outer surfaces of the sides of the strop 30 will contact therewith, while the inner surfaces of its sides will contact with the rollers or sleeves 21 while the front portions of the strop are extended between the outer rollers 16 on the rods 13 on the front portion of the frame. 105 When the parts are thus assembled, it is apparent that the frame may be secured to the wall of a room or other support, and that the blade of a razor may be located vertically between the jaws 26 of the retainer 23, when by drawing on first one end and then the other of the 110 strop 30, the members 19 will be caused to rock on their pivot 14, which operation will cause the retainer 23

to rock on its pivots or projections 29, so that first one side of the blade will be presented against one side of the strop and then the other side of the blade against the other side, so that in the reciprocation of the strop 5 the blade may be sharpened.

As one of the objects of my invention is to provide means for sharpening or stropping the blades of scissors, and as said blades require stropping on one side only, I have provided an attachment, which forms a 10 part of the invention, for holding the blade of a pair of scissors, which attachment consists of a plate or piece 31 having its rear portion formed with an enlargement 32 to fit between the jaws 26 of the retainer 23, and said plate, as well as said enlargement 32 thereon, may be 15 of any suitable length, but preferably somewhat shorter than the distance between the frame plates. The plate 31 is provided at its upper and lower ends with apertured lugs 33, which extend laterally from one side of the plate, and have located in their apertures a rod 34 20 on which is mounted an anti-friction roller or sleeve 35 against which one side of the strop 30 may contact. In front of the lugs 33, the plate 31 is provided with an angularly deflected portion 36, which is provided near its ends with horizontal slots 37, through which are 25 passed apertured lugs 38, produced on an adjustable jaw 39, which is bent to lie alongside of the portion 36 so as to clamp the scissors blade 40 between it and said portion, which may be done by means of set-screws 41 located in the lugs 38 of the adjustable jaw. It will be 30 observed by reference to Fig. 5 that the lugs 38 are extended towards each other so that the screws 41, when tightened, will rest against the surface of the angular portion 36, and that the slots will permit said lugs to be moved so as to adjust the jaw 39 to blades of different 35 widths and taper.

In Fig. 6 I have shown an attachment which is adapted to be used for holding a butcher or table knife,

which consists of two plates 42 and 43 secured together by solder or rivets so as to form at its rear portion an enlargement 44 to fit between the jaws 26 of the retainer, 40 and at its front edge with spaced apart jaws 45 between which the thickened portion of the knife or blade may be placed, so that its cutting edge may be presented to the sides of the strop.

In Fig. 7 is shown still another attachment for holding 45 knives of different constructions, which consists of plates or members 46 and 47 secured together to form an enlargement 44 to fit between the jaws 26 of the retainer 23, and its front edge spaced apart to receive thin blades. 50

Having thus fully described my invention, what I claim as new, and desire to secure by Letters-Patent, is—

In a stropping machine, the combination with the spaced apart frame plates each having at about its middle 55 a rearwardly extending slot and one of said plates having an opening in its front portion, of tie-rods uniting said plates, anti-friction rollers located between the frame plates, a pair of rocking members pivotally mounted between the frame plates, anti-friction rollers journaled on 60 said members between the same and in a line with its pivot, a retainer pivotally connected at its rear portion to the front portion of the rocking members and having projections at its ends to loosely engage the slots in the frame plates and provided at its front edge with adjustable jaws, a blade holding attachment consisting of an angular plate having near its rear edge an enlargement to fit between said adjustable jaws and provided at its upper and lower ends with apertured lugs, an anti-friction roller journaled on said lugs, a jaw adjustably held on the front 65 portion of the angular plate, and a strop extended around the anti-friction rollers on the rocking members and between the rollers of the frame plates, substantially as described. 70
